FIG. 1

FIG. 2

FIG. 3

FIG. 4

FIGURE 1 is a top plan view of a power cable suspension clamp embodying my new design;

FIGURE 2 is a side elevational view of the design taken from the lower side of FIGURE 1;

FIGURE 3 is an end elevational view of the design as viewed from the right hand end of FIGURE 2, the opposite end, not shown, being substantially the same in appearance.

FIGURE 4 is a side elevational view of the design taken from the upper side of FIGURE 1.

The fragmentary cables shown in FIGURE 2 in broken lines are for illustrative purposes only.

I claim:

The ornamental design for a power cable suspension clamp, as shown and described.
